SCISSORS

I. M. Laurenti, 432 Park Ave. S.,
New York, N.Y. 10016

Filed June 28, 1973, Ser. No. 374,363

Term of patent 14 years

Int. Cl. D8—03

U.S. Cl. D8—57

FIG.1

FIG.2

FIG.3

FIG.4

FIG.5

FIG.6

FIG.7

FIG. 1 is a top plan view of scissors showing my new design;

FIG. 2 is a side elevational thereof;

FIG. 3 is a bottom plan view;

FIG. 4 is a blade end elevational view;

FIG. 5 is a handle end elevational view;

FIG. 6 is a second embodiment of the design of FIG. 1;

FIG. 7 is a handle end elevational view of the second embodiment.

I claim:

The ornamental design for a scissors, substantially as shown and described.
